DETECTOR DEVICE

Elvin A. Mastriani, Cedar Grove, N. J., assignor
to The M. W. Kellogg Company, Jersey City,
N. J., a corporation of Delaware

Original application May 10, 1947, Serial No.
747,245. Divided and this application November
27, 1948, Serial No. 62,337

3 Claims. (Cl. 139—357)

1

The present invention relates to looms, and more particularly to electric warp stop mechanisms therefor. This application is a division of application Serial No. 747,245, filed May 10, 1947.

The conventional type of electric warp stop mechanism comprises a detector device in the form of parallel detector rods, each including a pair of contact bars insulated from each other and passing through a row of drop wires supported on respective warp threads. Each of the drop wires is adapted to fall and electrically interconnect the contact bars when the corresponding warp thread breaks. A knock-off or loom stopping device controlled by the detector device comprises a solenoid in the direct circuit of said detector device energized by the release of a drop wire occasioned by the breakage of the corresponding warp thread. The energized solenoid through its plunger actuates a member into position to be engaged by the lay during its movement, and thus initiate knock-off action of the loom.

The standard practice is to use a solenoid requiring low current in order to minimize arcing or sparking between the fallen drop wires and the corresponding contact bars. The solenoid will therefore be of low power, and as a result, will be of delicate construction requiring careful setting and adjustment.

The object of the present invention is to provide a new and improved electric warp stop mechanism.

As a feature of the present invention, the detector bar assembly is comparatively simple in construction, and affords vertical and angular adjustments with ease.

As another feature, a new and improved detector bar clamp is provided, locked by a cam lock affording ease of operation into and out of locking position.

As another feature, spacer bars for supporting the warp sheet and for separating the various rows or banks of drop wires, are provided secured by means of spring clips, so that these bars may be removed or replaced singly without disturbing the warp.

As another feature, electrical contact to the contact detector bars is established by means of spring clips, each of which engages two adjoining bars.

Various other objects, features and advantages of the invention will be apparent from the following particular description, and from an inspection of the accompanying drawings, in which—

2

Fig. 1 is a broken fragmentary perspective partly in section of a loom containing an electric warp stop mechanism embodying the present invention;

5 Fig. 2 is a broken plan view partly in horizontal section of the knock-off mechanism embodying the present invention, and shown during normal running operations of the loom;

10 Fig. 3 is a view similar to that of Fig. 2, but showing the knock-off mechanism at the instant it is operated, to shut down the loom upon detection of a broken warp thread;

15 Fig. 4 is a rear view of the contact bar supporting end of the detector device;

Fig. 5 is a fragmentary bottom section of the contact bar supporting end of the detector device;

20 Fig. 6 is a transverse section of the contact bar supporting end of the detector device taken along the lines 6—6 of Fig. 4;

Fig. 7 is a transverse section of the contact bar supporting end of the detector device taken along the lines 7—7 of Fig. 4; and

25 Fig. 8 is a wiring diagram of the electric system of the warp stop mechanism.

Referring to the drawings, the novel mechanisms of the invention may be applied to looms having any of the usual loomsides, but it is preferred to disclose the invention in connection with a loom provided with loomsides 10, the right loomside only being shown, each comprising a pair of parallel upstanding frame webs 11 and 12 rigidly secured together by suitable cross braces, (not shown). A lay 13 secured to swords 14 (only one being shown) is oscillated back and forth lengthwise of the loom. The swords 14 are angularly oscillated in any suitable manner in the spaces between the frame webs of corresponding loomsides.

30 40 The warp stop mechanism includes a detector device 15 mounted at each end to a bracket 16 supported on a plate 17 extending between and secured to frame webs 11 and 12, as for example, by welding. The detector device 15 comprises a series of parallel detectors 18 of the usual type, each comprising a pair of contact bars 20 and 21 insulated from each other. Drop wires 22 of the conventional type are arranged along each detector 18. The threads constituting the warp

35 45 50 55 of the fabric pass through the drop wires 22 forwardly toward the lay 13. Each of the threads supports an individual drop wire 22 out of contact with the contact bar 20. When a warp thread breaks, its wire 22 will fall into contact with the bar 20 and close the circuit between the bars

20 and 21. This initiates the operation of the knock-off mechanism.

The knock-off mechanism is supported as a unit in a housing 25 comprising a top wall 26, an outer side wall 27, and a front wall 28. The housing 25 is rigidly supported in position between the loomside frame webs 11 and 12. To that end, a platform 31 is supported on and extends between the upper ends of the loomside frame webs 11 and 12, and is provided with holes 32 (only one being shown) for receiving mounting studs for the housing 25. The top housing wall 26 has a plurality of threaded stud sleeves 33 located to register with respective holes 32 in the platform 31, and welded or otherwise rigidly secured to said top housing wall. By means of studs (not shown) passing through respective platform holes 32 and threaded into the sleeves 33, mounting of the housing 25 in position and removal thereof can be easily effected.

Secured to the outer housing wall 27, as for example, by studs (not shown), is a solenoid 35 having a plunger 36 movable in and out as the solenoid coil is energized and deenergized. Extending in the housing 25 in an axial direction substantially parallel to the direction of movement of the solenoid plunger 36 is a rocker shaft 37 supported in bearings 40 and 41 mounted on said housing. One of the bearings 40 in the form of a block is desirably welded to the housing walls 27 and 28, while the other bearing 41 also in the form of a block, is desirably welded to the top housing wall 26. A collar 42 affixed to the rocker shaft 37 limits outward slide movement of said shaft.

Spined to the rocker shaft 37 so as to rotate therewith and slide therealong is a knock-off finger or lever 43 urged outwardly along said shaft by a coil spring 44, which is located between the bearing 41 and the hub of the knock-off finger 43.

A link transmission between the solenoid plunger 36 and the knock-off finger 43 comprises a lever yoke 45 having at one end a cleft 46 pivoted to one end of a link 47, whose other end is pivoted to said plunger. The other end of the yoke 45 has a fork 48 straddling the rocker shaft 37 between the hub of the knock-off finger 43 and a spacer washer 50 bearing against the shaft collar 42. The yoke 45 is pivoted intermediate its ends to a post 51, rigidly secured to the housing 25 desirably by welding it to the top housing wall 26. A stud 52 threaded into the post 51 pivotally secures the yoke 45 to said post.

For actuating the knock-off finger 43 by the movement of the lay 13, there is secured directly to one side of the sword 14 a knock-off bunter 55. The sword 14 is shown of channel shape, and the bunter 55 is provided with a recess 56 to receive one of the flanges of the sword and is secured to the sword web, as for example, by means of studs 57.

While the solenoid 35 is deenergized, the lever yoke 45 is in the angular position shown in Fig. 2, so that the knock-off finger 43 is yieldably held by the coil spring 44 in position out of the oscillating path of movement of the bunter 55. Upon the energization of the solenoid 35 resulting from the breakage of a warp thread, the plunger 36 will be moved inwardly into the position shown in Fig. 3, so that the lever yoke 45 will be rotated clockwise about its pivot stud 52. This will cause the knock-off

finger 43 to be moved along the rocker shaft 37 against the action of the coil spring 44, until it is in the path of oscillating movement of the knock-off bunter 55. As the lay 13 moves rearwardly, the bunter 55 engaging the knock-off finger 43 in this position rotates said finger, and thereby causes a corresponding rotation of the rocker shaft 37. This rotation of the rocker shaft 37 is transmitted to the shipper handle (not shown), to shut down the loom. The shutdown is desirably effected without shutting down the motor by merely releasing or disengaging the clutch between the motor and the main crank shaft of the loom.

The transmission between the rocker shaft 37 and the shipper handle is of a non-positive character, and comprises a push rod knock-off lever 60, which is keyed to the part of the rocker shaft 37 projecting from the outer side of the housing 25, and which has a forked end 61 straddling a push rod 62 supported for slide movement in a pair of slide bearings 63 secured to the outer frame web 12. A return spring 65 encircles the push rod 62, and abuts at one end against one of the bearings 63, and bears at the other end against a collar 59, fixed to push rod 62, to urge the forked lever end 61 toward the other bearing 63.

In axial alignment with the push rod 62, and connected to the shipper handle (not shown), is a clutch release rod 67. The rod 67 is provided with a tappet sleeve 68, confronting the operating end of the push rod 62, and adapted to be engaged thereby when the push rod is moved to the left by the rotation of shaft 37 and lever 60, due to the engagement of knock-off finger 43 and knock-off bunter 55, as shown in Fig. 3.

The clutch release rod 67 carries a finger 70 which engages the spring pressed plunger 71 of the switch 72 during normal running operations to maintain the switch normally closed. The finger 70 disengages the plunger 71 to open the switch 72 when the rod 67 moves to the left for clutch release and loom shut-down operations initiated when the warp thread breaks and the corresponding drop wire 22 falls into position to establish contact between the bars 20 and 21. When switch 72 is in the open position, current cannot flow through the circuits of the warp stop mechanism and all hazards due to live circuits while the loom is stopped are eliminated.

The electrical arrangements for the warp stop mechanisms are shown in Fig. 8, and while they may be connected to a separate power supply, are conveniently connected to the power lines 80, provided as a current supply for the loom motor, not shown. A step down transformer 81 is connected across lines 80 to step the voltage down from the usual 220 volts to about 8 volts. The lines 82 are connected across the secondary coil of the transformer 81 and supply current to the solenoid 35. Since, as will be apparent, the current for the solenoid 35 does not go through the warp break detector circuit, the solenoid may be as large, and as powerful, as necessary for the positive operation of its associated elements and as much current as required by the solenoid 35 may be safely passed through lines 82 as such current does not feed through the detector circuit.

The lower one of the lines 82 is connected to the terminal A of the relay switch 83, while a short line 82' connects the terminal A' to the solenoid 35 to complete the solenoid circuit. The

relay switch 83 is of usual design and includes a relay coil 84, that when energized, operates through a plunger to move the switch element 85 from the normal full line position to the dotted line position, wherein it electrically connects the terminal A to the terminal A' and the terminal B to the terminal B'. A spring not shown, returns the switch element 85 to the full line position when the relay coil 84 is deenergized. A short lead connects the terminal A to the terminal B, while a second short lead connects the terminal B' to the relay coil terminal D. A second pair of lines 86, are connected across the secondary coil of the transformer 81. The upper one of lines 86 is connected to one terminal of the switch 72, shown in its closed position, and a short lead 86' connects the other terminal of the switch 72 to the terminal C of the relay coil 84. The lower one of the lines 86 is connected to the parallel bank of contact bars 21, the bank of bars 21 being grounded as shown, while a short lead 86'' connects the parallel bank of contact bars 20 to the terminal D of the relay coil. Since the relay coil is designed to actuate switch element 85 and its associated plunger, its current demand is quite low so that only a comparatively low current will flow through the warp break detector circuit. The bank of bars 21 is grounded to prevent an accumulation of current in the normal open circuit operation of the detector circuit.

Upon the breaking of a warp thread, the respective drop wire 22 will fall to close the gap between its pair of bars 20 and 21, so that current will flow through lines 86, 86' and 86'' to energize the relay coil 84 and move the switch element 85 to the dotted line position. This closes the circuit of the solenoid 35, so that solenoid 35 through its associated elements will move the knock-off finger 43 along shaft 37 into position to be engaged by the knock-off bunter 55. Since the switch element 85 in the dotted line position closes the gap between the terminals B and B', the terminal D is brought to substantially the same potential as the side of the secondary transformer coil to which the lower one of the lines 86 is connected and, consequently, the relay coil 84 will be energized by current flowing through the lower one of lines 82 and the leads between the terminals A and B' and D, while the lower one of the lines 86 and the banks of bars 20 and 21 will be effectively cut out of the electrical circuits. This results in an uninterrupted energization of the relay coil 84 and the solenoid 35, which cannot be influenced by the movements of the drop wire 22 on its bars 20 and 21 during the interval between the initiation of knock-off operations and the completion thereof when the bunter 55 by engagement with the knock-off finger 43 rotates the shaft 37 and the lever 60 to move the clutch release rod 67 to the left to disengage the clutch between the motor and the main drive shaft (not shown), and simultaneously to open the switch 72 to the dotted line position.

When the switch 72 is open (the dotted line position) the relay coil 84 and the solenoid 35 are deenergized and no current whatsoever can flow through any of the circuits just described. Said interval may, according to the speed of the loom, amount to as much as one-half a second and in the arrangements of the prior art the hazards due to arcing and sparking because of movement of the drop wire 22 on the live bars 20 and 21 during this interval is of a serious nature. All such hazards are eliminated in the present construction as arcing and sparking cannot take

place since the bars are dead. Also, since switch 72 remains open during the thread repair period, or any other period when the clutch disengages the loom motor from the main drive shaft, all hazards due to live electrical circuits during loom down time are eliminated.

After the warp thread is repaired and the drop wire 22 is returned to its normal position the clutch is again actuated to engage the loom motor to the main drive shaft and the clutch release rod 67 moves to the right so that the finger 70 again closes the switch 72. As the lay 14 moves away from knock-off position, springs 44 and 65 will return the parts of the knock-off mechanism automatically to their normal operating positions. This may take place as the lay is coming to rest after knock-off or when the lay is again started, depending on the timing and the setting of the loom brake according to the weaving conditions.

While the electrical circuits have been described above in connection with an A. C. power source, it is obvious that they are not limited to the use of an A. C. source, but with simple changes, well within the knowledge of the skilled worker in the yard, they can be used equally well with a D. C. current source.

The detector device 15 is mounted for horizontal and vertical adjustment. The bracket 16 has a base 90 seated on the plate 17 and adjustably secured thereto by means of a bolt (not shown), passing through said base and through an elongated slot 91 in said plate, which permits adjustment of the detector device along the plate 17.

For vertical adjustment, the bracket 16 has a vertically elongated slot 93 receiving a locking bolt 94 passing through a boss 95 at one end of a detector bar holder 96.

The detector bar holder 96 is of U-shaped cross-section, and comprises a base 97 having a series of parallel grooves 98 for receiving the lower edges of the detector rods 18, and a pair of upstanding ears 100 at each end.

For clamping the detector rods 18 in position, and for transmitting current thereto, there is provided at each end of the detector device 15 a bar clamp 101. The bar clamp extends between the ears 100 of the holder 96, and is pivoted thereto by means of pivot studs 102.

Secured to the underside of the bar clamp 101 is a conductor strip 104 provided with a terminal 105 for attachment of a conductor wire thereto, and insulated from said bar clamp by an insulating pad 106. Fastened to the underside of the bar clamp 101, and in conductive contact with the conductor strip 104, is a series of contact springs 107 shown in the form of bowed leaf springs secured to said clamp by screws 108, and each yieldably bearing against the upper edges of two adjoining contact bars 20.

For releasably locking the bar clamp 101 in position, there is provided a handle 115 having a cam 116 at one end bearing against a wear washer 114 on said bar clamp. The cam 116 is of forked construction, and has pivoted thereto the upper end of a bolt 117 passing through a hole 118 in the bar clamp 101, and extending into a hole 120 in the bar holder 96. The lower end of the bolt 117 has an elongated key 121, and the hole 120 has a keyhole conformation corresponding to the shape of said key 121.

When the bolt 117 is locked in position against axial withdrawal, the handle 115 may be turned about its pivot support with said bolt to cam the bar clamp 101 down tightly, the clamping pressure depending upon the angular position of said handle. When it is desired to lift the bar clamp

101 about its pivot supports for adjustment or repair of the detector rods 18, the handle 115 is turned to rotate the bolt 117 until its key 121 is in registry with the keyhole 120. The bolt 117 can then be lifted out of the bar holder 96.

For supporting the warp sheet, there are secured to opposite sides of the bar holder 96 guide bars 125. Additional members 126 between the guide bars 125 are provided for further supporting the sheet, and for separating the various rows or banks of drop wires 22. These additional members are shown in the form of spacer bars removably retained in spring clips 127 and 128 secured to the underside of the bar holder 96. The end clips 127 are shown in angular form secured in position by respective studs 130, while the intermediate slips 128 are U-shaped to engage adjoining spacer bars 126, and are secured in position by respective studs 131 passing through the base sections of respective clips.

While the invention has been described with particular reference to a specific embodiment, it is to be understood that it is not to be limited thereto, but is to be construed broadly and restricted solely by the scope of the appended claims.

What is claimed is:

1. In a warp stop mechanism for a loom, an electric detector device comprising a plurality of detector rods, each including a pair of contact bars insulated from each other, and a holder for said rods at one end, comprising a base on which said rods are seated, a clamp pivoted to said base and adapted to overlie the ends of said rods, and cam means for locking said clamp with adjustable pressure against said rods, said cam means including a handle having a cam at one end adapted to bear against said clamp, and a bolt

5 pivotally secured near one end of said cam, passing through said clamp, and having a releasable key engagement at its other end with said base.

2. In a warp stop mechanism for a loom, an electric detector device comprising a plurality of detector rods, each including a pair of contact bars insulated from each other, a holder for said rods at one end comprising a base on which said rods are seated, a clamp pivoted to said base and adapted to overlie the ends of said rods, and a series of contact springs in the form of bowed leaf springs, each secured to said clamp and each yieldably bearing against the upper edges of two adjoining contact bars.

10 3. In a warp stop mechanism for a loom, an electric detector device comprising a plurality of detector rods, a holder for said rods at each end, a row of drop wires arranged along each detector rod, and means for separating the various rows of drop wires comprising spring clips secured to said holder, and spacer bars removably retained in said spring clips.
